UNITED STATES PATENT OFFICE.

HOMER W. WYCKOFF, OF INDIANAPOLIS, INDIANA; NATHAN H. RICHARDSON
ADMINISTRATOR OF SAID HOMER W. WYCKOFF, DECEASED.

WIRE-CONNECTOR.

No. 902,040.

Specification of Letters Patent.

Patented Oct. 27, 1908.

Application filed March 12, 1906. Serial No. 305,529.

To all whom it may concern:

Be it known that I, HOMER W. WYCKOFF, a citizen of the United States, residing at Indianapolis, in the county of Marion and State of Indiana, have invented new and useful Improvements in Wire-Connectors, of which the following is a full, clear, concise, and exact description, reference being had to the accompanying drawing, forming a part 10 of this specification.

My invention relates to wire connectors for connecting electrically or mechanically two or more wires used for conducting electricity.

15 The object of my invention is to provide a connector that will clamp the wires firmly in a locked position for ordinary use; that can be quickly opened without injuring the connector for testing and other purposes; that 20 will serve for connecting together either wires of the same size or wires of different sizes; that can be applied to join continuous wires, a wire end to a continuous wire, or two wire ends; and that will conform to variations 25 in diameters of different sized wires.

My invention is especially applicable to telephone and telegraph wires of copper, at points where it is desired to open the main line at times, or where it is desired to connect 30 a branch wire to a continuous main wire. Two main telephone or telegraph wires to be connected in this manner will usually be of the same size, No. 12 (diameter .104") and No. 14 (diameter .080"), being the two sizes 35 of copper wire commonly used in telephone construction. In case of "legging" a branch wire to a continuous main telephone wire, the main wire will ordinarily be numbered 12 and the branch wire No. 14 in size. While 40 No. 12 and No. 14 wire is the wire most commonly used in telephone construction, various other wires are used, the difference in diameter of which varies from .016" or less to 0.040", and it is one of the objects of my 45 invention to provide a connector which may accommodate any combination of wires, even though their variation be as much as .040".

In the accompanying drawings, which show one embodiment of my invention, Fig. 50 1 is an isometric view of my connector; Fig. 2 is a partial sectional view of my invention; Fig. 3 is a modified form of my invention; and Figs. 4, 5 and 6 show the manner in which different wires may be connected.

55 As shown in Fig. 2, the plate *a* has a hole *j*

in the center, slightly larger than the shank of the bolt *d*, so as to allow some play for lateral adjustment of the grooves upon the wires. The other plate *b* has a corresponding hole through its center for the screw-thread *k* of the bolt. The turning of the bolt will thus draw the two plates *a* and *b* together upon the wires. The nut *e*, also screwing on the thread *k*, serves as a lock nut, when screwed tightly against plate *b* to prevent loosening of the contact upon the wires by wind or other sources of vibration acting upon them. The thread in the plate may be omitted to cheapen the cost of construction or for other purposes, or the lock nut 60 may be omitted when the threaded plate is used. The end *k* of the bolt is battered down or headed over slightly as at *k'*, to prevent the parts of the clamp becoming detached and lost, and the head *c* of the bolt 65 may be grooved for a screw driver. The plates, however, may be separated sufficiently to allow the wire to be passed between the same at the sides when necessary.

The opposed faces of the plates *a* and *b* are 70 provided with grooves *f* and *g* to receive the wires. These grooves in cross section or end view, Figs. 1, 2 and 3 are formed with the same radius which is at least as large as that of the largest wire to be used. The two 75 exactly similar grooves *f*, however, are cut less deep in the plates as shown, than the exactly similar grooves *g*, by a depth equal to the average difference in radii between two wires of unequal size that may be used together. 80

As hereinbefore stated, the difference between diameters of wires used in combination may possibly vary from .016" or less, to .040", and it will be evident that it would be impossible with one type of connector to 85 practically make the difference in depth of the grooves conform with the various differences of wires and still preserve the parallelism of the outer surfaces of the plates.

The combinations of wires most commonly 90 used by telephone companies are as follows:

#18 B. & S. (diam. .040") and #14 N. B. S. (diam. .080")—difference between diam. .040".

#14 B. & S. (.064") and #14 N. B. S. 100 (.080")—difference between diam. .016".

#14 N. B. S. (.080") and #12 N. B. S. (.104")—difference between diam. .024".

It is also possible that the following combinations will be used:

#18 B. & S. (.040") and #14 B. & S. (.064")—difference between diam. .024.

#16 N. B. S. (.064") and #12 N. B. S. (.104")—difference between diam. .040".

5 I have adopted an average difference of .028" (.014" for each plate) for the difference in depths of the wire grooves and propose to take up the variation from this average difference, amounting to .012" each way, by 10 thickening the plates in the middle and thus providing for slanting plane or curved surfaces extending from each side of the middle to the edges, on the outer faces of the plates, and adapted to take up this slight variation 15 mentioned, when the plates are clamped together. It will be noted that if the difference between the diameters of two unequal wires used in the connector (see Figs. 2 and 3) is greater than the average, as is the case with 20 .064" and .104" wires, the outer surfaces of the plates to the left of the middle line, that is, upon the side toward the larger wire, will be practically parallel, giving good bearing under the bolt head and nut. Similarly, if 25 the difference in diameters of the wires, is less than the average difference, as is the case with .064" and .080" wires, the outer surfaces of the plates to the right of the middle line, that is, toward the smaller wire, will be 30 practically parallel, and there will be good bearing under the bolt head and nut. In fact, if the outer face of each plate along the middle line is slightly rounded, there would be sufficient bearing in all cases. The 35 grooves in the connector can be varied to accommodate any size of wire, so that the connector is not limited to use with wires mentioned herein.

It is easily seen that this connector is 40 adapted for use with two wires of the same diameter by simply turning one plate half way around the bolt, while the other plate remains stationary. Groove *f* in the plate *a* is then opposite groove *g* in *b*, and groove *g* in 45 plate *a* will be opposite groove *f* in plate *b*. If, now, two No. 12 wires are placed in the connector, it will be seen that on account of all grooves having been cut with at least as large a radius as that of wire 12, the wires 50 will come into good contact with the bottoms of the grooves, and on account of the diameters of the wires being the same and the full depth of grooves *f* and *g* equaling the full depth of grooves *g* and *f* at the other side 55 in plates of the form shown, the outer faces of the plates will still offer good bearing for the bolt head *c* and the nut *e* as before. Reduction in the size of two equal wires will still preserve the contacts at the bottoms of 60 the grooves. Thus it is seen that by thickening each plate along the middle line, or in other words, providing the outer faces of the plates with ridges or surfaces sloping very slightly from the middle line to each side of 65 the plate, to permit a slight rocking of the

plates under the bolt head and the nut, the connector is efficiently adapted for use with wires of various diameters even if the difference in diameters may not exactly conform with the difference in depth of the grooves. 70 Also, as to the rocking of the plates under the bolt head and nut, it is easily seen that the plate that is not cut with a screw thread, has sufficient play to permit of a slight rocking, and with reference to the plate tapped 75 with the screw thread there is sufficient play in the thread and in the elasticity of the material to permit that also to rock the small amount that is required.

While the connector may be made of any 80 suitable metal, it is desirable to have the plates made of the same metal as the wire to be joined, and that the whole be reasonably non-corrosive. For copper wire, as heretofore indicated, it is preferable to make the 85 connector with copper plates and brass bolt and nut. Cheaper metals, plated or otherwise protected against corrosion may, however, be used.

From the above, it will be noted that my 90 connector is efficiently adapted to the various uses set forth, and may be used in many relations for other purposes.

I wish to be understood that I do not desire to be limited to the exact details of construction shown and described for obvious modifications will occur to a person skilled in the art. 95

Having thus described my invention what I claim as new and desire to secure by Letters Patent, is:

1. In a wire-connector, in combination, two metal plates having opposed inner faces for receiving wires therebetween upon opposite sides of the longitudinal center of the 105 plates, said metal plates having surfaces slanting from the middle to the sides thereof, and means for clamping the plates together.

2. In a wire-connector, in combination, two metal plates having opposed inner faces, 110 each of said faces being provided with grooves upon opposite sides of the longitudinal center thereof, the grooves of each face registering with the grooves in the other face, the outer faces of said metal plates having surfaces slanting from the middle to the sides thereof, and means for clamping the plates together. 115

3. In a wire-connector, in combination, two metal plates having opposed inner faces, 120 each of said faces being provided with grooves upon opposite sides of the longitudinal center thereof, the grooves of each face registering with the grooves in the other face, the outer faces of said metal plates having surfaces slanting from the middle to the sides thereof, and a bolt passing through 125 said plates to clamp the same together.

4. In a wire-connector, in combination, two metal plates having opposing inner faces, 130

each of said faces having substantially parallel grooves of different cross section registering with the grooves in the other face, the outer faces of said metal plates having surfaces slanting from the middle to the sides thereof, and a bolt passing through said plates to clamp the same together.

In witness whereof, I have hereunto subscribed my name in the presence of two witnesses.

HOMER W. WYCKOFF.
